UNITED STATES PATENT OFFICE.

ERNST MÜHL, OF PHILADELPHIA, PENNSYLVANIA.

STEAM-CONDENSING TURBINE.

1,346,413.

Specification of Letters Patent.

Patented July 13, 1920.

Application filed September 9, 1919. Serial No. 322,608.

To all whom it may concern:

Be it known that I, ERNST MÜHL, a citizen of the United States, residing at Philadelphia, in the county of Philadelphia and 5 State of Pennsylvania, have invented certain new and useful Improvements in Steam-Condensing Turbines, of which the following is a specification.

One object of my invention is to provide 10 a steam turbine construction in which the internal parts, such for example as the turbine wheel and its connecting elements, will operate in a partial vacuum due to the condensation of the steam immediately adjacent 15 said elements and thereby reduce friction of said elements during their movement and permit them to freely operate in a better manner than possible in constructions made prior to my invention.

20 Another object is to so construct my invention that it will develop greater power than heretofore possible in turbine machines of this type when utilizing similar quantities of steam under the same pressure; my 25 invention being operative to develop great power while using a small amount of steam under a comparatively low pressure.

A further object is to make my invention 30 of a simple and strong construction so that the parts can be cheaply and quickly manufactured and put together.

These objects, and other advantageous ends which will be described hereinafter, I attain in the following manner, reference 35 being had to the accompanying drawings in which—

Figure 1 is a side elevation of my invention,

Fig. 2 is a top plan view of Fig. 1, 40 Fig. 3 is a section taken on the line 3—3 of Fig. 2,

Fig. 4 is a transverse section taken on the line 4—4 of Fig. 3,

Fig. 5 is a fragmentary elevation partly 45 in section showing certain of the features of my invention,

Fig. 6 is a transverse section taken on the line 6—6 of Fig. 5,

Fig. 7 is a side elevation of one of my improved compound nozzles,

Fig. 8 is a fragmentary section taken on the line 8—8 of Fig. 7,

Fig. 9 is an enlarged fragmentary view 55 of a part of an inclined trough or gutter providing a waterway and forming a part of my invention,

Fig. 10 is a fragmentary enlarged section through the turbine wheel and taken on the line 10—10 of Fig. 3,

Fig. 11 is a sectional elevation of similar 60 nature to Fig. 4 showing a modified form of my invention including a plurality of turbine wheels and associated parts together with a number of said troughs providing a plurality of waterways for the condensing 65 water and water of condensation, and

Fig. 12 is a fragmentary face view of one of the turbine wheels shown in Fig. 11.

Referring to Figs. 1 to 10 inclusive of the drawings, 14 represents a casing or steam 70 chest made in two hollow parts 15 and 16 in which the part 16 serves as a base section and the part 15 serves as a hood or top section. Bearings 17 are provided at opposite sides of the casing 14 and serve as support- 75 ing means for a shaft 17^a; said shaft passing transversely through the casing 14 and having a turbine wheel 18 secured thereon within the casing; a part of the turbine wheel being closed by the base section and 80 a part by the top section of said casing as clearly shown in Figs. 3 and 4.

A steam inlet pipe 19 is connected to a box 20 providing a steam inlet chamber 21; said box 20 being secured to one end of the 85 casing 14 as clearly shown in Figs. 5 and 6. Nipples 22 extend through the casing 14 and form means for attachment for steam headers 23 within the casing 14. These steam headers have two nozzles 24 respectively secured thereto; said nozzles being positioned at opposite sides of the turbine wheel 18 as clearly shown in Figs. 4 and 5. The nipples 22 provide means of entrance of the steam from the chamber 21 95 into the headers 23 and each of the nozzles 24 is made arcuate as shown in Fig. 7 and is provided with two arcuate ducts 25 which taper at their inner ends as shown at 26, said inner ends leading to the side surfaces 100 27 immediately adjacent the opposite side surfaces of the turbine wheel 18. Thus, comparatively small holes 28 provide outlets for the steam directly adjacent the side surfaces of the turbine wheel. The sides of 105 the turbine wheel are provided with steam expansion pockets 29 and 30 (see Fig. 10); said pockets tapering inwardly; the pockets on opposite sides being in staggered relation as clearly shown in Fig. 10 so that a 110 maximum depth can be given to the pockets on opposite sides without piercing or in-

terfering in any manner and are comparatively large. Also by thus making the pockets comparatively large, spaces are provided for the steam expansion as will hereinafter be more fully described. The nozzles 24 are also provided with two arcuate channels; said channels 31 being made up of a succession of pockets 32; said pockets being comparatively shallow adjacent the steam outlet holes 28 and are of various depths and are arranged in step formation; the depths being graded so that the pockets which are the greatest distance from the holes 28 are the deepest, as clearly shown in Fig. 8. The pockets 29 of the turbine wheel 18 are arranged in annular rows as clearly shown in Fig. 3 and the arcuate channels 31 of the nozzles 24 are so shaped as to be directly opposite or in register with the pockets 29 of the turbine wheel. The steam passes outwardly through the holes 28 in the nozzles and expands within the pockets 29 of the turbine wheel 18 which are immediately adjacent the holes 28. This steam further expands into the shallow pockets 32 in the channels and the impulse of thus pocketing and permitting the expansion of the steam causes the rotation of the turbine wheel 18. By having the pockets 32 of gradually increasing depths the steam is permitted to expand and at the same time during the expansion within the length of the channel 31 additional impulse will be established due to the fact that the steam expands into the various pockets so that the re-action of said steam is to add additional advancing force to the turbine wheel. The steam after passing out of the free ends of the channels 31 is admitted into the upper portion of the casing 14.

One side of the casing 14 is open as shown at 33 and a supplemental casing 34 is secured to the casing 14 and provides a chamber 35, as clearly shown in Fig. 3. The supplemental casing and chamber extend below the bottom of the opening 33 and provide a water chest for a purpose hereinafter to be described. A cold water pipe 36 enters the supplemental casing 34 and has a substantially horizontal extension 37 which is longitudinally perforated adjacent its bottom and extends substantially the entire width of the casing 14. A bolt 38 extends through the casing 14 and supports the inner end of the extension 37 of the water pipe 36. A trough or chute 39 has its inner end supported by the bolt 38 and inner end of the water pipe extension 37; said trough being arranged at an incline and being made up of a number of sections 40 which are substantially U-shape in cross section. These sections 40 are secured to each other as clearly shown in Figs. 3 and 4 by screws 41 so that there is a space 42 between each two of the sections; said spaces being lo-

cated at the bottom of the chute so as to permit the steam, as indicated by the arrows in Figs. 3 and 9, to pass into the chute through the spaces 42. Cold water is fed into the water pipe 36 from any suitable source and falls in streams into the chute 39. These streams of cold water intercept the stream within the upper portion of the casing 14 and thereby condenses the steam and the water of condensation and the water from the water pipe falls into the chute and runs downwardly into the bottom of the chamber 35; it being noted that the lowermost section of the chute rests upon the casing 19 at the bottom of the opening 33.

This sudden condensation of the steam causes a partial vacuum to be established within the casing and thereby reduces the friction of the movable parts permitting them to move more freely and eliminates back pressure of any character.

It will be noted that by having the openings 42 between the sections of the chute that the steam will pass through said spaces and directly engage the streams of cold water so as to quickly condense the steam which rises under the chute. The water from the chamber 35 is taken off by a pipe 43 and can be injected into a steam boiler or used for any other purpose desired.

By the provision of the parts as above described a great saving of steam is effected due to the formation of the parts of the partial vacuum and also by utilizing the expansive and impulsive action of the steam throughout the entire length of the pocket channel 31.

The bottom of the casing 14 is provided with a valve 44 whereby any drainage can be drawn off and this valve is preferably made in the form of a trap valve so as not to interfere with the establishment of a vacuum within the casing as above described.

In the form of my invention shown in Figs. 11 and 12, I have illustrated a number of turbine wheels 18^a which are connected to a shaft 17^b. In this instance I have illustrated a number of sprinkler or water pipes 37^a which are connected to an outer inlet water header shown in dot-and-dash lines 110 at 45. Troughs 39^a are positioned under each of the water pipes 7^a. Furthermore, I have illustrated each of the nozzles 24 as being provided with a number of pocketed channels 31^a for registering with the pockets 29^a of the turbine wheels 18^a. In this manner any number of turbine wheels can be practically secured to one shaft and the concerted result of the expansive and impulsive action of the steam between the nozzles and their adjacent turbine wheels will be such as to impart power to said shaft.

While I have described my invention as taking a particular form, it will be understood that the various parts of my invention

may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

- 5 10 15 20 25 30 35 40 45 50 55 60 65 70 75
- 10 1. A steam turbine including a casing; a water pipe leading into said casing; a trough spaced from said water pipe whereby water from said pipe impacts with the steam in said casing to condense the steam and passes through the space between the water pipe and the trough; and means for taking off the water from said trough; substantially as described.
2. A steam turbine including a casing into which the steam is exhausted; a perforated water pipe in said casing; a trough made in sections and spaced from the perforations in said water pipe whereby water passes through said space into the trough, said sections having spaces therebetween whereby steam can enter said trough to impact with the water; and means for taking off said water from the trough; substantially as described.
3. A steam turbine having a casing into which the steam is exhausted; a longitudinally perforated water pipe extending into said casing and an inclined trough spaced from said water pipe whereby the water from said pipe passes in streams through said latter space into the trough; and means for taking off the water from the bottom of said inclined trough; substantially as described.
4. A steam turbine having a casing into

which the steam is exhausted and having an opening; a supplemental casing communicating with said first casing through said opening; a water pipe leading into said first casing through the supplemental casing; a chute spaced from said water pipe whereby water from said pipe passes through said latter space to condense said exhaust steam, said chute having a portion leading into said supplemental casing whereby the water is delivered into said supplemental casing; and means for taking off the water from said supplemental casing; substantially as described.

5. A steam turbine having a casing into which the steam is exhausted and having an opening; a supplemental casing communicating with said first casing through said opening; a water pipe leading into said first casing through the supplemental casing; a chute spaced from said water pipe whereby water from said pipe passes through said latter space to condense said exhaust steam, said chute having a portion leading into said supplemental casing whereby the water is delivered into said supplemental casing; and means for taking off the water from said supplemental casing, said chute being connected to said water pipe whereby the water pipe and chute can be removed through said opening when said supplemental casing is removed; substantially as described.

In testimony whereof I have signed my name to this specification in the presence of two subscribing witnesses.

ERNST MÜHL.
